UNITED STATES PATENT OFFICE.

FRANKLIN HARDINGE, OF CHICAGO, ILLINOIS, ASSIGNOR TO THE HARDINGE BROTHERS COMPANY, OF CHICAGO, ILLINOIS, A CORPORATION OF ILLINOIS.

WATCHMAN'S CLOCK.

1,267,406.

Specification of Letters Patent. Patented May 28, 1918.

Application filed February 7, 1913. Serial No. 746,718.

To all whom it may concern:

Be it known that I, FRANKLIN HARDINGE, a citizen of the United States, residing at Chicago, in the county of Cook and State of Illinois, have invented a certain new and useful Improvement in Watchmen's Clocks, of which the following is a full, clear, concise, and exact description, reference being had to the accompanying drawing, forming a part 10 of this specification.

My invention relates to improvements in watchmen's clocks adapted to make a characteristic record upon a record receiving dial or disk contained within the clock casing 15 when actuated in connection with marking mechanism, which is usually located at various points within the building or territory to be covered by the watchman.

In connection with the watchman's clock 20 of my invention I provide means adapted to make a record upon the dial or disk every time the clock casing is opened. This means takes the form of a knife adapted to puncture the dial whenever the locking devices 25 for securing the hinged clock-back in closed position are moved to their non-locking position. I have found that whenever a knife having a straight cutting edge is used for puncturing the record dial, the paper of which 30 the dial is made is quite likely to be torn as the puncturing operation is accomplished; thus leaving free edges which often-times are caught by the various clock devices as the dial rotates. In order to avoid this difficulty I provide the dial puncturing member with a crescent shaped cutting edge and so disposed with respect to the dial that the crescent cut will have its ends pointing in the direction of rotation of the dial and the 35 free edges of the cut portion in the opposite direction; thus when the cut portion comes into contact with the recording or clock mechanism the free ends will be brought toward the plane of the body of the dial. I 40 have found that when such a cutting edge is provided the paper dial may be punctured without in any way tearing the same or pre-

senting any free edges to be caught in the clock mechanism.

My invention is illustrated in the accompanying drawings in which;

Figure 1 is a rear elevational view of the watchman's clock of my invention with the hinged clock-back in open position.

Fig. 2 is a fragmentary sectional view 55 taken on the line 2-2 of Fig. 1; and

Fig. 3 is a fragmentary sectional view taken on the line 3-3 of Fig. 2.

Similar reference numerals refer to similar parts throughout the several views. 60

As illustrated, the watchman's clock of my invention comprises a casing 4 to which is hinged at 5 the usual clock-back 6. The said casing is provided with a pair of rings 7-7 to which a strap may be attached in 65 order that the clock may be easily carried by the watchman. These rings are also designed to serve as legs, as shown in Fig. 1.

Disposed within the casing 4 is the clock movement, a portion of the casing for said 70 movement being illustrated at 8. Driven at a uniform rate by the clock mechanism is a dial 9 preferably made of paper. Secured to the casing 4 by means of screws 10 is a recording mechanism 11. This recording 75 mechanism is adapted to make a characteristic record upon the dial 9 whenever a suitable key is inserted in the keyway 12, and the cam lever 13 of the operating mechanism is actuated. With this particular recording mechanism the present invention is, however, not particularly concerned.

I will now describe the means provided for locking the clock-back 6 in closed position and for making a record upon the dial every 85 time the clock back is unlocked. As clearly illustrated in Fig. 2, the clock-back 6 is provided with a loop 14, which is adapted to be engaged by a locking lever 15, pivoted at 16 to a bracket 17, carried by the clock casing. 90 In Fig. 2 the lever 15 is shown in its locking position. The dial 9 is disposed behind the bracket 17, as shown. Pivoted to the bracket 17 is a plate 18, which is provided with a

slot 18^a, as shown. This slot 18^a when the devices are in the position shown in Fig. 2, is adapted to register with an opening 17^a extending through the bracket 17. Disposed in the opening 17^a is a cutting member 19, which at one end is pivoted to an arm 20 of the locking lever 15.

A compression spring 21 acting between the front side of the bracket 17 and the arm 10 20 normally retains the locking lever in the position illustrated in Fig. 2 and retains the cutting member 19 out of engagement with dial 9.

Having bearings in the clock casing and a 15 bracket 22, is a disk 23 which may be readily rotated by means of a key inserted in a key-hole 24. The said disk is provided with a cam portion 25, as most clearly shown in Fig. 3.

20 Assuming the parts to be in the positions shown in the drawings and the disk 23 is rotated in the direction indicated by the arrow, the cam portion 25 of the disk is brought between the lever 15 and the clock 25 casing, thus forcing the hook of the locking lever out of engagement with loop 14 and at the same time bringing the member 19 into engagement with dial 9 to record that the clock-back has been unlocked from the casing and moved to an open position.

I have found that if the cutting member 19 is provided with a straight cutting edge 35 it will almost invariably tear the paper dial a trifle as the puncturing of the dial is effected. If the dial is torn there is quite apt to be free edges present which are likely to 40 be caught in the recording mechanism 11 as the dial is rotated. In order to avoid this difficulty, I provide the cutting member 19 with a crescent-shaped cutting edge 26, which makes a clean cut incision in the clock 45 dial, and having the ends of the cut pointing in the direction of rotation of the dial, so that there are no free edges present to be caught in the recording mechanism 11, and so affect the operation of the watchman's clock.

While I have illustrated my invention in 50 the particular embodiments herein shown and described, I do not wish to be limited to these particular constructions but desire to claim broadly any equivalents thereof which may suggest themselves to those skilled in the art.

55 What I claim is:

1. A watchman's clock comprising a casing, a movable dial within the casing, said clock casing having one side thereof arranged to permit access to the dial, means 60 for locking said side in closed position, and devices comprising a member having a substantially crescent-shaped edge adapted to make a cut upon said dial when said side is

unlocked from said casing, the crescent shaped cut made by said member having its 65 ends pointing in the direction of movement of the dial to prevent the cut portion of the dial from being caught in the mechanism disposed immediately adjacent thereto.

2. A watchman's clock comprising a casing, a movable dial within the casing, said casing having one side thereof arranged to permit access to the dial, and means comprising a member having a substantially crescent-shaped cutting edge adapted to cut the 75 dial to indicate upon said dial the fact that said side has been moved from its closed to an open position, the crescent shaped cut made by said member having its ends pointing in the direction of movement of the dial 80 to prevent the cut portion of the dial from being caught in the mechanism disposed immediately adjacent thereto.

3. A watchman's clock, comprising a casing 85 provided with a hinged member, and devices for locking said hinged member in closed position, a movable dial within the casing, a knife provided with a substantially crescent-shaped cutting edge, and devices 90 adapted to bring said edge into engagement with the dial to cut the same when said member is unlocked from said casing, the crescent-shaped cut made by said knife having its ends pointing in the direction of movement 95 of the dial to prevent the cut portion of the dial from being caught in the mechanism disposed immediately adjacent thereto.

4. A watchman's clock comprising a casing, a movable dial within the casing, a hinged back for said casing, and means comprising a member having a substantially crescent-shaped cutting edge for making a record on said dial in the form of a cut when 100 said back has been opened, the crescent shaped cut made by said member having its 105 ends pointing in the direction of movement of the dial to prevent the cut portion of the dial from being caught in the mechanism disposed immediately adjacent thereto.

5. A watchman's clock comprising a casing, 110 a movable dial within the casing, and means comprising a member having a substantially crescent-shaped cutting edge adapted to make a record on said dial when said casing is opened, the crescent shaped cut 115 made by said member having its ends pointing in the direction of movement of the dial to prevent the cut portion of the dial from being caught in the mechanism disposed immediately adjacent thereto.

6. A watchman's clock comprising a casing, a movable dial within the casing, a back for said clock, means for locking said back in position, and means comprising a member having a substantially crescent-shaped cutting edge to cut said dial when said back is 125

unlocked from the casing, the crescent shaped cut made by said member having its ends pointing in the direction of movement of the dial to prevent the cut portion of the dial from being caught in the mechanism disposed immediately adjacent thereto.

5 7. A watchman's clock comprising a casing, a movable dial within the casing, and means for making a substantially crescent shaped cut in the dial having its ends pointing in the direction of movement of the dial

to prevent the cut portion of the dial from being caught in the mechanism disposed immediately adjacent thereto.

In witness whereof, I hereunto subscribe 15 my name this 22nd day of January, A. D., 1913.

FRANKLIN HARDINGE.
